UNITED STATES PATENT OFFICE.

VOTAW S. DURBIN, OF ST. LOUIS, MISSOURI, ASSIGNOR TO DURBIN AUTOMATIC TRAIN PIPE CONNECTOR COMPANY, OF ST. LOUIS, MISSOURI, A CORPORATION OF ARIZONA.

AUTOMATIC TRAIN-PIPE CONNECTOR.

1,074,849.

Specification of Letters Patent.

Patented Oct. 7, 1913.

Application filed April 27, 1912. Serial No. 693,650.

To all whom it may concern:

Be it known that I, VOTAW S. DURBIN, a citizen of the United States, residing in the city of St. Louis and State of Missouri, have 5 invented new and useful Improvements in Automatic Train-Pipe Connectors, of which the following is a specification.

This invention relates to certain new and useful improvements in automatic coupling 10 attachments for the signal, brake and steam pipes of railway cars.

The invention relates to the type of train pipe connector described and illustrated in my pending application, Ser. No. 658,667, 15 filed November 6, 1911, and involves improvements in the construction and operation of such device.

The present invention, therefore, has for 20 its general objects to provide an improved manner of supporting the connector as a whole from the car; to provide improved means for maintaining the coupler-heads in their interlocked relation under the ordinary conditions of service, thereby preventing 25 relative movement between the two coupler-heads; and to provide means for automatically and positively unlocking the coupler-heads.

Further objects of the invention reside in 30 details of construction and combinations of parts, all of which will be more clearly understood from the description and claims to follow.

In the accompanying drawings - Figure 1 35 is a view in side elevation of the forward portion of two coupled cars showing the train pipe connector in coupled relation; Fig. 2 is a similar view showing the position of the parts when the cars are uncoupled; Fig. 3 is a central, transverse, sectional view through two coupled connectors; Fig. 4 is a horizontal sectional view of the same; Fig. 5 is a view in front elevation of 45 one of the connector heads; and Fig. 6 is a fragmentary, sectional view showing the contact devices for establishing electrical connection through the connector heads.

Referring now to the drawings, the numerals 1 and 2 indicate, respectively, the 50 meeting ends of two cars, each of which has extending across its end at the bottom a piece of timber 3 called the dead-wood.

4 indicates generally the draft couplers.

The two members of my device being alike 55 in all particulars, and being supported on

each car in exactly the same manner, a description of one, and the manner of supporting it, will suffice for both.

The numeral 5 indicates a housing which is preferably cast in two parts and joined together by rivets, or the like, 6. Secured on the under side of the car, and depending therefrom, are two supports 7, to the lower ends of which is secured a casting 8, the front side of which is recessed to receive a 60 tapered and apertured end 9 of the casing 5, and is provided in opposite sides with bearings 10 to receive a pivot pin 11 which passes through the aperture in the end of the casing, and is journaled in the said bearings 10. The bottom and top of the recess 65 in the casting 8 form stops 12 and 12^a, respectively, the lower stop serving to limit the downward movement of the casing 5, and to support said casing should the chains 70 hereinafter referred to break or become disconnected from the coupler; and the upper stop serving to limit the upward movement of said casing to prevent any tendency to buckling in the coupling operation. The 75 forward end of the casing 5 is provided with an opening 13 through which projects a plunger 14 having within the casing a head 14^a between which and the rear end of the casing is provided a coil spring 16 which 80 extends normally to push the plunger 14 outward. The outer end of the plunger 14 is bifurcated and apertured, and in the bifurcated portion 15 there is inserted a substantially circular, apertured projection 16^a 85 formed on the rear side of the coupler-head 17, and a pin 18 is passed through the apertures in the bifurcated end of the plunger and in said projection whereby the coupler-head is pivotally mounted upon said plunger. A cotter-pin 19 is used to hold the pin 18 in place. The movement of the coupler-head on its pivot 18, as will be observed, is in a plane at right angles to the movement of the casing 5 upon its pivot 11; and in 90 this way I provide for movement of the coupler-head in all necessary directions, thereby securing the advantages of a universal joint, while providing a stronger, and at the same time, more economical construction. 95

The coupler-head, as a whole, is substantially of the construction shown in my pending application, being provided with a pyramidal projection 20 on one side for entering 100

110

an opening in the mating head, and adjacent to said projection being provided with an opening 21 for receiving the pyramidal projection on the mating head. The projection 5 20 is hollow, and near its base in its outer wall is provided with an opening 21^a through which projects a locking-catch 22, mounted on a lever 23, which lever is pivotally mounted at 24 at one end on the coupler-head. At its opposite end the said lever is provided with an eye 25 in which is secured one end of a chain 26, the opposite end of which is connected to the end of the casing 5, as indicated at 27. One end of a 10 spring 28 is also connected in the eye 25, the other end of said spring being secured at the apex of the projection 20, as indicated at 29. The coupler-heads of the train pipe connector project considerably in advance of 15 the corresponding coupling members of the draft coupler, and when the cars are brought together, therefore, the coupler-heads of the train pipe connector first engage and interlock, and by the time the draft couplers 20 have also interlocked the plungers 14 will have been pressed back a considerable distance in the casing 5 against the resistance of the springs 16. When the cars are uncoupled and start to separate the plungers 30 14 will, of course, be pressed outward by the said springs 16, and as the coupler-head moves away from the end of the casing 5 the chain 26 will hold the inner end of the lever arm 23 from movement so that the 35 catch 22 will thereby be drawn inward as the lever arm 23 turns on its pivot, being thereby moved from engagement with the wall 30 of the mating coupler-head. This occurs before the plungers 14 have completed 40 their outward movement, so that by the time the coupler-heads are ready to separate the catch 22 will have been completely withdrawn, allowing the coupler-heads to freely 45 separate. When the cars are brought together, and as the plungers 14 are pressed backward, the spring 28 will gradually pull the end of the lever 23 outward until the catch 22 again projects through the opening 21 and over the wall 30 of the mating coupler-head. In this way the two coupler-heads are securely locked in position, and so long as the cars are coupled these two coupler-heads cannot be separated by any 50 force less than that required to break them, or, at least, the catches 22. Each coupler-head is provided with suitable apertures, adapted to aline, for the passage of fluid, said apertures being indicated by the numerals 31, 32 and 33, the apertures 31 and 32 55 at the upper part of the coupler being for suitable connection with the brake and signal pipes, and the aperture 33 being for connection with the steam pipe. In the case of the air ports each of the apertures 31 and 32 is surrounded with an interiorly screw-

threaded housing 34, 35, in which is first inserted a rubber gasket 36, the end of which projects slightly beyond the face of the coupler for engagement with the opposing gasket. A nipple 37, having an outer threaded end 38 and a shouldered head 39, is then inserted to bear against the gasket 36, and a nut 40 is screwed into the housing, its inner end bearing against the head 39 of the nipple and pressing it firmly against the rubber gasket. By screwing up the nut 40 at different times the rubber gasket 36 can be pressed outward to make up for wear, contraction, etc. The air pipes 41 and 42 are inserted on the ends of the nipples, as shown. In the case of the steam pipe connection, I omit the rubber gaskets and mount the contact members 43 in the meeting ends of the nipples 44, on which the steam pipes 44^a are inserted. In each coupler-head I likewise mount contact pins 45 surrounded by insulation 46, to which pins are connected wires 47 so that when the coupler-heads are brought together these contact pins will firmly engage each other and render it possible to establish telephonic communication throughout the length of the train. 70 80 85 90 95

When the cars are in the uncoupled position the coupler-heads and casings 5 are supported by means of chains 48 connected at their upper ends to the dead-wood, and at their lower ends to lugs on the coupler-heads, as indicated at 49. The length of these chains is such that, as shown in Fig. 2, when the cars are uncoupled they will be drawn taut as the plungers 14 are pressed outward, and will thereby hold the connectors as a whole in a substantially horizontal position. When the cars are coupled, however, and the plungers pressed inward, these chains will be slackened, as shown in Fig. 1, permitting the requisite up and down movement of the connectors, such as occurs in the movement of the train due to unevenness in the track, and the like. 100 105 110 115

As the pull on the chain 26, due to the pressure of the spring 16, would, if not resisted, turn the coupler-head 17 to one side, I provide on the wall 30 of each coupler-head an eye 51 to which is connected one end of a chain 50, the other end of which is connected to the end of the casing 5, as indicated at 52. This chain, as will be apparent more clearly from an examination of Fig. 4, holds the coupler-head from being turned by the means stated beyond the correct coupling position. 120 125 130

I claim:

1. In combination with a car having train pipes, a rigid member supported from the car affording a bearing, a cylindrical casing having its rear end pivotally mounted in said bearing to oscillate vertically, stops provided on said member for limiting the 130

movement of said casing on its pivot in either direction, a coil spring housed in said casing, a plunger extending through the front end of the casing and having a head 5 working in the casing against said spring, a coupler-head pivotally mounted on the outer end of the plunger and having a movement about its pivot in a plane at right angles to the movement of the casing about 10 its pivot, and being provided with ports for the passage of fluid, means for maintaining said coupler-head normally in the coupling position, and hose-attaching means carried by said coupler-head and communicating with said ports.

2. In combination with a car having train pipes, a casing pivotally supported at one end from said car, a spring-pressed plunger housed in said casing, a coupler-head pivotally mounted on the end of said plunger, a locking member pivotally mounted on said coupler-head at one side thereof, a spring connected at one end to said locking member, and at its other end to the coupler-head, 25 a connection between said end of the locking member and the end of said casing, and a connection between the other side of said coupler-head to that described and the said casing, said locking member being 30 adapted to engage a part of the mating coupler-head under the influence of its spring when the two coupler-heads have been brought together and the plungers forced inward.

3. In a train pipe coupling, in combination with a spring-controlled plunger supported from the car, a coupler-head having a hollow tapered projection for entering an opening in, and provided with an opening for receiving a corresponding projection on, 40 the mating coupler-head, and said projection having an opening in its wall, a lever pivotally mounted on the head at one end, a spring connected at its opposite ends to the other end of said lever and to said coupler-head, respectively, means connecting the said free end of the lever with a relatively fixed member on the car, and a locking member carried by said lever and working through said opening in the projection 45 of the head, said locking member being adapted to engage a part of the mating coupler-head under the influence of said spring when the coupler-heads are brought together and the plunger forced inward, and 50 to be withdrawn from such engagement by the said connecting means when the plunger is forced outward by its spring as the heads are drawn apart by the separation of the cars.

In testimony whereof, I have hereunto set my hand in presence of two subscribing witnesses.

VOTAW S. DURBIN.
